U. S. PATENT OFFICE.

No. 72.

1861.

WHOLE No. 1,437.

Window Shade Material.

GIBBONS L. KELTY, OF NEW YORK, N. Y.

Letters Patent for a Design, No. 72, dated July 9, 1861.

SPECIFICATION.

TO ALL WHOM IT MAY CONCERN:

Be it known, that I, GIBBONS L. KELTY, of the city and State of New York, have invented, made, and applied to use, a new and original Design for Painted Window Shade Material; and I do hereby declare that the following is a full, clear, and exact description of the said design, reference being had to the annexed specimens of the said material.

For the manufacture of window shades or curtains, it is usual to paint the design upon prepared muslin or similar fabric, the said design being adapted to a given size of window.

My said invention is a new and original design for a manufacture consisting of an ornamental lattice painted upon the prepared fabric of which window shades or curtains are made, said design extending over the entire surface of the lengths or pieces of material, so that the desired size for the window shade can be cut out regardless of the pattern.

The accompanying specimens illustrate this new and original design for the manufacture of window shades or curtains, the ornamental lattice, of whatever color it may be composed, extending over the entire surface, as shown.

What I claim, and desire to secure by Letters Patent, is—

The new and original design for the manufacture of window shades or curtains set forth, the same consisting of an ornamental lattice painted upon the entire surface of the fabric, as shown.

In witness whereof, I have hereunto set my signature this twenty-seventh day of April, 1861.

GIBBONS L. KELTY.

Witnesses:

THOS. GEO. HAROLD,
LUDWIG SONDEHEIM.
